IDA BROWN
BY *Bradley L. Benson*
ATTORNEY

UNITED STATES PATENT OFFICE.

IDA BROWN, OF SAN FRANCISCO, CALIFORNIA.

HOSE-SUPPORTER CLASP.

1,421,061.

Specification of Letters Patent. Patented June 27, 1922.

Application filed August 11, 1921. Serial No. 491,378.

To all whom it may concern:

Be it known that I, IDA BROWN, a citizen of the United States of America, residing at 1882 19th Avenue, San Francisco, in the county of San Francisco and State of California, have invented certain new and useful Improvements in Hose-Supporter Clasps, of which the following is a specification.

The present invention is an improved hose 10 supporter clasp of the type used to support a stocking and usually dependent from a corset, belt, band or other article of wearing apparel.

The primary object of the invention is, to 15 provide a securing means for the upper end of a stocking which is readily attachable thereto or detachable therefrom, and which, when attached, will accommodate itself to various changes of bodily position of the 20 wearer, without undue strain on the fabric of the stocking. Particularly, on ladies' stockings, the tendency of the rigid clasps now in common use, is to break stitches in the fabric and thus produce what are called 25 runners. This one feature causes great loss to users, who are compelled to discard stockings which otherwise would be serviceable for a long time.

In the device hereinafter described, the 30 securing means is not a rigid engagement of the stocking, by the clasp, but, on the contrary, it allows a pivotal movement of the clasp relative to the stocking and thus accommodates itself to different angular positions of the leg of the wearer, and the 35 tendency to cause runners is entirely eliminated.

Other objects and advantages, such as 40 economical production and simplicity, will appear as this description proceeds.

In this specification and the annexed drawings, the invention is illustrated in the form considered to be best, but it is to be understood that the invention is not limited to 45 such form, because it may be embodied in other forms, and it is also to be understood that in and by the claims following the description it is desired to cover the invention in whatever form it may be embodied.

50 In the accompanying one sheet of drawings;

Fig. 1 is a front elevation of my improved clasp.

55 Fig. 2 is a section of Fig. 1 on the line II-II.

Fig. 3 is view similar to Fig. 1, but showing the clasp engaging a fragment of stocking fabric.

Fig. 4 is a section of Fig. 3 on the line IV-IV.

Fig. 5 is an enlarged section of Fig. 3 on the line V-V.

Referring to the drawings, the numeral 1 indicates a strip of fabric secured at the top to a corset, belt or band, and at the bottom returned as indicated at 2 to engage and support a wire eye 3, of conventional form, provided with the usual constricted channel portion 4 at the bottom. The parts so far described are well known and form no part 70 of my invention.

To the back of the strip of fabric 1, I secure the ends of a relatively narrow strip of tape 6 forming a loop dependent from the strip 1. Before the ends of the strip of tape 6 are secured, I pass the tape through a rubber ring or button 7, in such a manner that the ring 7 is suspended from the strip 1 in a loop formed by the narrow tape 6.

I purposely make this loop of a length 80 greater than that of the eye 3, so that when the parts are assembled, as in Fig. 1, the major portion of the ring 7 extends below the bottom end of the eye 3.

The object of this is to eliminate all strain 85 of support from the loop or tape 6 when the clasp is secured to a stocking as shown in Figs. 3 and 4. My invention differs in this respect from most supporters. It is customary to make the strip which carries the knob or button (which is engaged by the channel 4) of approximately the same length 90 as that of the eye 3.

As a result, when the stocking is engaged between the two parts of the clasp, both are 95 under equal strain, and the stocking and both members of the clasp are locked together rigidly, and if the bodily position of the wearer is changed, the parts are moved in unison and a torsion applied to the fabric 100 of the stocking.

As will be later described, my clasp permits relative movement of the parts and of the fabric and prevents this torsional strain 105 on the fabric.

When my clasp is to be attached to a stocking, the fabric 8 is inserted between the eye 3 and the ring 7. The fabric 8 and the ring 7 are held securely, and the eye 3 extended downwardly until the enlarged portion 9 of 110

the eye allows the eye to be pressed down over the ring 7, which is now closely covered by the fabric 8. A pull upwardly will now engage the parts in the position shown 5 in Figs. 3 and 4. It will be seen that the constricted channel 4 prevents the disengagement of the stocking and that there is nothing extending through said channel but the fabric of the stocking and the loop 6 10 which is not under tension.

Thus engaged, the clasp is free to rotate as indicated by the dotted lines in Fig. 3, the eye 3 having a free movement relative to the stocking fabric 8.

15 Obviously, the ring 7 may be a disc or button of any suitable material, and the loop 6 might be a tongue or single strip, and the button or ring integral therewith, without departing from the spirit of my invention, 20 but I prefer to make my clasp as shown, and I find that a rubber ring affords frictional engagement which assists in holding the fabric.

I claim:—

1. A hose-supporter clasp, comprising a 25 strip of material, an eye dependent from said strip and provided with a restricted channel, a loop dependent from said strip and a ring engaged by said loop and adapted to co-act with said eye and channel to hold a stocking 30 fabric.

2. A hose-supporter clasp, comprising a strip of material, an eye dependent from 35 said strip and provided with a restricted channel, a loop dependent from said strip, and a rubber ring engaged by said loop and adapted to co-act with said eye and channel to hold a stocking fabric.

3. A hose-supporter clasp comprising a strip of material, an eye dependent from 40 said strip and provided with a restricted channel, a loop attached to said strip, and a ring threaded on said loop, the said loop of a length greater than that of said eye.

In testimony whereof I affix my signature. 45
IDA BROWN.
